US0D1021894S

(12) **United States Design Patent** (10) Patent No.: **US D1,021,894 S**
(45) Date of Patent: ** Apr. 9, 2024

(54) **SMARTWATCH**

(71) Applicant: **Zhenyun Zhang**, Hengyang (CN)

(72) Inventor: **Guangzhou Du**, Shenzhen (CN)

(**) Term: **15 Years**

(21) Appl. No.: **29/875,790**

(22) Filed: **May 10, 2023**

(51) LOC (14) Cl. **14-02**

(52) U.S. Cl.

USPC **D14/344**

(57) **CLAIM**

The ornamental design for a smartwatch, as shown and described.

DESCRIPTION

FIG. 1 is a front elevation view of a smartwatch showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof;

FIG. 9 is a perspective view thereof, showing the smartwatch in a position of use; and,

FIG. 10 is another perspective view thereof, showing the smartwatch in a position of use.

The broken lines depict portions of the smartwatch and form no part of the claimed design.

The other broken lines in FIGS. 9 and 10 are included to show environmental subject matter only and form no part of the claimed design.

1 Claim, 10 Drawing Sheets
